Hoquet & Neary

UNITED STATES PATENT OFFICE

ALBERT P. LEONARD, OF NEW YORK, N. Y.

BAFFLE FOR HEAT EXCHANGERS

Application filed February 8, 1928. Serial No. 252,948.

The present invention relates to heat exchange apparatus and, more particularly, to juice heaters such as those employed in the sugar industry. Primarily the invention 5 consists in conducting hot vapors through a heat exchange chamber at a substantially uniform velocity, the construction of the chamber being such that the cross-sectional area of the passage through which the heating 10 medium flows is progressively diminished. In this manner the velocity of the heating medium is maintained at a substantially constant value and, not only is a better heat transfer therefore obtained, but the heavier 15 non-condensable gases are carried along with the heating vapor to an outlet therefor. The constant discharge of the non-condensable gases prevents these gases from settling near or around the walls or tubes of the apparatus, 20 at which points the gases would ordinarily tend to insulate the tubes and prevent proper heat exchange. The lighter gases are, of course, carried away by the heating vapor.

It has previously been proposed to obtain 25 a constant velocity of the heating medium by progressively and continuously reducing the diameter of the heating chamber from the inlet to the outlet thereof. Various arrangements of baffles have also been suggested, 30 but a satisfactory application of these suggestions to heaters of the return tube type having a uniform drum diameter has not heretofore been made. The present invention aims to provide in a heater of the tubular type a novel arrangement of baffles whereby 35 a constant velocity of the heating medium, conducted through the heating chamber in a direction parallel to the tubes, is maintained. It further provides an arrangement of passages 40 for the heating vapors whereby the length of the apparatus is materially reduced and there is relative heat exchange between said passages so that there is a greater available temperature difference between the 45 heating medium and the material heated thereby. The invention will be more clearly understood from the following description of a preferred form of heater, taken in connection with the accompanying drawings, in 50 which:

Figure 1 is a sectional side elevation of the heater;

Figure 2 is a front elevation partly in section;

Figure 3 is a sectional elevation taken on the line 3—3 of Figure 1; and

Figure 4 is a detail of the method of fastening the baffles to the drum sheets.

As illustrated in Figure 1 of the drawings, the heater comprises a cylindrical drum 10 which is supported on suitable legs 10'. To the ends of the drum are secured, in any suitable manner, headers 11, 12 for the tubes 13. The drum is provided with an inlet 14 and outlets 15 and 16, the former for condensed liquids and the latter for air and gases. It will be seen that each of the headers is provided with partitions 17 so arranged that the medium to be heated is forced through the tubes in a circuitous course, the medium in each horizontal row of tubes flowing in a direction opposite that in the tubes of the adjacent horizontal row. To each header is hinged a cover 18, and secured to the cover by bolts or other suitable fastening means are gaskets 19. Plates 20 secured to the covers act as liners to hold the gasket in position with its respective cover. One header, which for convenience will hereinafter be termed the front header, is provided with an inlet 21 and an outlet 22, between which are the partitions 17 cooperating with the cover 18 to form a number of chambers which communicate with similar chambers in the opposite or rear header. The partitions in the front header are arranged in staggered horizontal relation with those in the rear header, so that material entering the inlet 21 flows in alternate directions through adjacent horizontal rows of tubes before being discharged through outlet 22.

The drum is divided horizontally to provide two oppositely directed passages 23, 23' for the steam or other heating medium. The steam inlet and outlets are located at the front end of the drum so that the steam first flows from one end of the drum over the upper rows of tubes to the rear end of the drum and is then returned over the lower rows of tubes. Division of the drum is obtained by

a number of baffles 24, 24' and 24" disposed within the drum in stepped relation, the baffle at the rear end of the drum being disposed in a substantially medial plane and the other baffles successively lowered toward the front end of the drum. The rearmost baffle is spaced from the rear header to provide communication between the upper and lower passages 23, 23'. In this manner the passage for the steam is successively reduced in cross-section from the inlet to the outlet, the decrease in volume due to condensation being counteracted by the reduced cross-sectional area of the passage, thus maintaining a substantially uniform velocity of the steam.

The manner in which the baffles are secured to the drum sheets provides a flexible connection between the baffles and the drum, and eliminates distortion and buckling of the baffles and drum. Each of the baffles has side flanges 25 which are bent to form a curve having a relatively large radius. The edges of the flanges are welded to the drum sheet, as shown at 26, to permit relative play between the baffles and the drum sheets, the curved portions of the flanges 25 acting as expansion joints. At one end of each baffle is a depending flange 27 which acts as a curtain for the heating medium and condensed liquids; each of these depending flanges is spaced a slight amount from the adjacent and next lower baffle to permit condensates or non-condensable gases, such as air, to flow into the passage 23' and to the bottom of the heater; but the gap between these flanges and the adjacent baffles is so small that there is little or no effect on the pressure of the steam in the upper passage 23. Directly under the steam inlet is an additional baffle 29 for deflecting the incoming steam toward the front header.

As shown in Figure 1, perforated tube supporting plates 33 are secured to the drum at suitable intermediate points between the ends of the drum, and at another intermediate point an expansion joint 30 is provided. If desired, safety valve and air vent flanges 31 and 32 are secured to the drum, and suitable condensate gauges may also be attached to the drum and header as indicated by flanges 34 and 35.

From the above description it will be seen that cane juices, or other material to be heated, are introduced into the front header and forced through the tubes circuitously, as explained above. The steam enters one end of the drum above the lowermost baffle, the cross-sectional area of the upper passage being greatest at this point; as the steam enters the drum it is directed against the front header by the baffle 29. It then expands and flows through the upper passage, the succeeding baffles progressively reducing the cross-sectional area of the passage, and, due to the arrangement of the baffles, the

cross-sectional area of the lower passage is also progressively reduced.

At each stepping up of the baffles a gap is left at the end of the lower baffle. The condensate resulting from the condensation of the heating vapors on the tubes fall to the baffle plate and the gap permits the condensate to flow to the bottom of the shell from whence it is removed. Heavy non-condensable gases such as air also flow downwardly through these gaps, thus preventing stratification of such gases above the upper side of the horizontal baffles and blanketing of the heating surface by these gases. It is desirable that the outlet for the gases be at a reduced pressure and for this purpose the outlet 16 may be connected to a vacuum chamber or suction pump, thus insuring proper discharge of these gases.

While the apparatus described above is referred to as a juice heater, it is obvious that the construction is applicable to other heat exchange apparatus, and it is therefore not intended to limit the invention to heaters employed for the specific purpose outlined above.

What I claim is:

1. A heat exchange apparatus of the class described comprising a heating chamber and a plurality of partition members within said chamber arranged in stepped longitudinal relation to progressively diminish the cross-sectional area of said heating chamber.

2. A heat exchange apparatus of the class described comprising a heating chamber, and a plurality of partition members within said chamber for dividing said chamber into communicating adjacent passages, said members being arranged in stepped longitudinal relation to progressively diminish the cross-sectional area of said passages.

3. A heat exchange apparatus of the class described comprising a heating chamber, a header secured to each end of said chamber, a plurality of tubes within said chamber and communicating with said headers, and a plurality of partition members for dividing said chamber into communicating adjacent passages, said members being arranged parallel to said tubes in stepped longitudinal relation to progressively diminish the cross-sectional area of said passages.

4. A heat exchange apparatus of the class described comprising in combination a heating chamber and a plurality of partition members within said chamber for dividing said chamber into adjacent passages, said members being arranged in stepped longitudinal relation to progressively diminish the cross-sectional area of said passages, one of said members being spaced from the end of the chamber adjacent said uppermost member to provide communication between said passages.

5. A heat exchange apparatus of the class

described comprising a heating chamber, and a plurality of adjacent partition members arranged in stepped longitudinal relation to progressively diminish the cross-sectional area of said chamber, one end of each of said members having a depending flange, said flange being spaced from the adjacent partition member.

5 6. In a tubular heat exchanger, a baffle positioned to progressively diminish longitudinally the cross-sectional area of flow through said heat exchanger.

10 7. In a tubular heat exchanger, a longitudinal baffle positioned to progressively diminish longitudinally the cross-sectional area of flow through said heat exchanger, an inlet positioned at the point of the maximum cross-sectional area and an outlet at the point of the minimum cross-sectional area.

15 20 8. In testimony whereof, I have signed my name to this specification.

ALBERT P. LEONARD.
